UNITED STATES PATENT OFFICE.

CHARLES F. KETTERING AND WILLIAM A. CHRYST, OF DAYTON, OHIO, ASSIGNORS TO
THE DAYTON ENGINEERING LABORATORIES COMPANY, A CORPORATION OF OHIO.

ELECTRICAL SYSTEM FOR ENGINES.

1,401,337.

Specification of Letters Patent. Patented Dec. 27, 1921.

Original application filed July 16, 1914, Serial No. 851,259. Divided and this application filed February 17, 1916. Serial No. 78,894.

To all whom it may concern:

Be it known that we, CHARLES F. KETTERING and WILLIAM A. CHRYST, citizens of the United States of America, residing at Dayton, county of Montgomery, and State of Ohio, have invented certain new and useful Improvements in Electrical Systems for Engines, of which the following is a full, clear, and exact description.

10 The present invention relates to an improvement in electrical systems and associated devices.

The present application is a division of our copending application, Serial No. 851,259, filed July 16, 1914.

One of the objects of the present invention is to combine a rheostat with an electrical system, in such a manner that said rheostat may be automatically shifted from time to time, relative to a co-operating contact, so as to present different surfaces to said contact.

This intermittent shifting of the rheostat tends to prevent burning and pitting of the resistance element thereof, and also to prevent undue wear on any particular portion of said rheostat.

Further objects and advantages of the present invention will appear from the following description, reference being had to the accompanying drawings, wherein one preferred form of the present invention is clearly illustrated.

In the drawings:

Figure 1 is a diagrammatic view of the electrical circuits, connections and devices which may be employed in the present invention.

Fig. 2 is a view, partly in elevation and partly in section of a casing, wherein the rheostat and certain associated mechanism is mounted.

Fig. 3 is a detail showing the rheostat or resistance unit removed from the casing.

Referring to the drawing, and more particularly to Fig. 1, the numeral 20 designates an electric machine, capable of operation as a generator, to supply current to the storage battery 21, or to work circuits and their associated devices.

This generator in the present instance is

shown as having a shunt field winding 22, one end of which is connected to the line wire 23, while the opposite end thereof is connected to a resistance element 24. The amount of resistance which is adapted to be cut into the field circuit and placed in series with the field winding 22, is controlled by the contact element 25, which, as will appear hereinafter, is automatically actuated in accordance with the speed of the engine.

The electrical system, including the resistance element and its combination with certain other features of said system, have been clearly described, illustrated and claimed in our Patent No. 1,272,055, issued July 9, 1918, and it is therefore deemed unnecessary to give a further description of this system in the present application.

As has been described above, the amount of resistance which is to be cut into the field circuit, is controlled by the contact element 25, which in turn is actuated in accordance with the speed of the engine. This contact element is so arranged that as the speed of the engine increases or decreases, said element will be moved relative to the resistance unit 24, in such a manner that a part of said contact element will wipe over the resistance material 26 included in said unit.

Now, if the same part of this resistance unit 24 were continuously engaged by the contact element, it would tend to cause an undue amount of wear on the particular portion of the resistance with which the contact engages. There would also be a tendency for the adjacent coils of the resistance unit to pit and burn and thereby render the system inefficient if not entirely inoperative.

In Fig. 2 a casing 27 is illustrated, which may form the front end of the generator 20. This casing is provided with compartments, in one of which is positioned the gear wheel 28, which forms a direct driving means from the engine to the movable elements herein-after described. This gear wheel is provided with spiral teeth 29 which mesh with a pinion 30, which in turn is mounted upon a sleeve 31. The sleeve 31 in turn is slidably mounted upon the main shaft 32, which is mounted within a compartment formed in the end housing 27 on the bearings 28.

The main shaft 32 is preferably of hollow construction and is adapted to receive one end of the cam-carrying element 33. Intermediate the ends of the shaft 32, there is 5 provided a centrifugal device 34, which includes an element 35, pivoted to the shaft 32 at the point 36, and connected to a slidable collar 37, by means of the arms 38, one end of which are secured to the collar 37, while 10 the opposite ends are secured to said centrifugal element 35.

As will appear from the heretofore mentioned co-pending application, this centrifugal element tends to automatically control 15 the advance and retard of the time of occurrence of the sparking impulses in the ignition circuit, but the details of construction for effecting this function have been omitted from the present application for the sake 20 of brevity.

However, this same centrifugal element tends to control the amount of resistance which is cut into and out of the field circuit, in accordance with the speed of the engine.

25 The manner in which this centrifugal element controls the resistance of the field circuit will now be described.

The collar 37, to which the centrifugal element is connected, is provided with a peripheral groove 38, wherein a bearing member 39, shown in dotted lines in Fig. 2 is positioned. This bearing element is carried by an arm 40, one end of which is pivoted as at 41, to one of the walls of the end housing 27. The opposite end of said arm is 30 formed into a contact wiper 25, clearly shown in Fig. 2, and lies in such position that it will pass over the resistance spool or reel 24, at such times as the said arm is 35 moved by the operation of the centrifugal member 34.

The resistance reel or spool 24 is formed of suitable insulating material and is preferably grooved, as is shown in Fig. 3, to receive 45 a resistance wire 26, the opposite terminals of which are connected to the terminal posts 42 and 43 respectively, in any suitable manner, see Figs. 1 and 2.

Now, in order to prevent undue wear of 50 the resistance wire or material, mechanism is provided, whereby the said spool or reel will be actuated to present, intermittently, different surfaces of said resistance wire or material for the contact wiper to pass over, 55 thus substantially distributing the wear over the entire surface of the resistance spool.

This mechanism comprises a pawl 44, pivotally mounted at 45, in such a manner that as the lug 46, carried by the arm 40, 60 reaches its maximum upward movement, said pawl will be tripped so as to engage with the ratchet teeth 47, formed on the upper end of the spool 24, and thus impart a slight rotative movement to said spool. 65 Any suitable means may be provided to pre-

vent the operation of said spool 24 in a direction other than that in which the pawl 44 tends to move the same.

It will of course be understood that as the contact arm 40 again assumes its normal position, the pawl mechanism 44 will be returned to its normal position, and will therefore be ready to again be actuated by the contact arm 40, when it again reaches its maximum upward movement. 70

While the form of mechanism herein shown and described, constitutes a preferred form of embodiment of the invention it is to be understood that other forms might be adopted, all coming within the scope of the 80 claims which follow.

What we claim is as follows:

1. In a rheostat, the combination with a movable support carrying resistance material; of a movable contact member; and 85 means actuated by the movement of the contact member for moving the support whereby to present different portions of the resistance material to the action of the contact member. 90

2. In a rheostat, the combination with a movable support carrying resistance material; of a movable contact member; and 95 means intermittently actuated by the movement of the contact member for moving the support whereby to present different portions of the resistance material to the action of the contact member. 100

3. In a rheostate, the combination with a rotatable support carrying resistance material; of a contact member movable over 105 said material; and means actuated by the movement of said contact member intermittently to effect the rotation of said support whereby to present different portions of the resistance material to the action of the contact member. 110

4. In a rheostat, the combination with a resistance carrier carrying resistance material, said resistance carrier being provided 115 with a ratchet; a contact element operable to cut in or out said resistance; a pawl element intermittently operable to coöperate with the said ratchet for changing the position of the resistance material, so as to 120 present different surfaces thereof to the contact element.

5. In a rheostat, the combination of a spool-shaped resistance carrier carrying resistance material and provided with a 120 ratchet; a contact element operable to cut in or out said resistance; a pawl element co-operating with the ratchet and intermittently operated by the contact element to change the position of the resistance, so as 125 to present different surfaces thereof to the contact element.

6. In a rheostat, the combination with a rotatably mounted cylindrical resistance carrier; carrying a spirally wound resistance 130

wire; of a ratchet provided upon said carrier; a pivotally mounted lever carrying a pawl; and a movable member carrying a contact and provided with a lug for engaging
5 said lever upon a predetermined movement of the movable member in a certain direction.

In testimony whereof we affix our signa-

tures in the presence of two subscribing witnesses.
